UNITED STATES PATENT OFFICE

135,119

DESIGN FOR A FLAG OR SIMILAR ARTICLE

Gottlieb J. Huwyler, Harrison, Maine

Application July 10, 1942, Serial No. 107,484

Term of patent 7 years

To all whom it may concern:

Be it known that I, Gottlieb J. Huwyler, a citizen of the United States of America, residing at Harrison, county of Cumberland, and State of Maine, have invented a new, original, and ornamental Design for a Flag or Similar Article, of which the following is a specification, reference being had to the accompanying drawing, forming a part thereof wherein the figure is a face view of a flag or similar article, showing my new design.

I claim:

The ornamental design for a flag or similar article, as shown.

GOTTLIEB J. HUWYLER.
